[57] CLAIM

The ornamental design for a guitar body, as shown and described.

DESCRIPTION

FIG. 1 is a top, front perspective view of a guitar body showing my new design;

FIG. 2 is a front elevational view thereof;

FIG. 3 is a rear elevational view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is a top, front perspective view of a second embodiment of the guitar body shown in FIG. 1;

FIG. 9 is a front elevational view of the second embodiment thereof;

FIG. 10 is a rear elevational view of the second embodiment thereof; and,

FIG. 11 is an enlarged fragmentary cross sectional view taken along line 11—11 of FIG. 9.

The broken line showing of a guitar neck and hardware is for illustrative purposes only and forms no part of the claimed design.

FIG. 3FIG. 6

FIG. 7

UNITED STATES PATENT AND TRADEMARK OFFICE
CERTIFICATE OF CORRECTION

PATENT NO. : Des. 336,487
